UNITED STATES PATENT OFFICE

99,860

DESIGN FOR A TEXTILE FABRIC

Curt Erwin Forstmann, Montclair, N. J.

Application October 14, 1935, Serial No. 58,979

Term of patent 14 years

To all whom it may concern:

Be it known that I, Curt Erwin Forstmann, a citizen of the United States, residing at Montclair, in the county of Essex and State of New Jersey, have invented a new, original, and ornamental Design for Textile Fabric, of which the following is a specification, reference being had to the accompanying drawing, forming part thereof.

In the drawing, the sole figure of which is a plan view of a piece of the textile fabric embodying the design of the present invention, the cloth depicted is of a single color.

The design is a reticulate pattern consisting of spaced groups of yarns extending both warpwise and weftwise, defining squares. Alternate groups *a* consist each of a plurality of parallel fine yarns, while the intervening groups *b* comprise each a pair of parallel coarse yarns. The surfaces of the squares show coarse stitches elevated above the general level of the groups of fine yarns.

I claim:

The ornamental design for a textile fabric as shown and described.

CURT ERWIN FORSTMANN.
